BOTTOM AND BACK BRACE FOR DRAG-LINE BUCKETS

Grant W. Trundle, Fort Lauderdale, Fla.

Application April 26, 1951, Serial No. 223,035

3 Claims. (Cl. 37—135)

This invention relates to an improvement in excavating apparatus and has particular reference to the type commonly recognized as drag line buckets and the prime purpose of the present invention is the provision of brace means for protecting the bucket against damage that is caused by impact engagement upon rocks or the like.

It is a commonly recognized fact, that drag line buckets have a relatively short life and require constant and repeated repairs to maintain the bucket bottom straight in order to facilitate the loading and discharge of excavated material. Attempts have been made to strengthen the bottoms of the buckets by using a plurality of ribs or runners along the bottom and back of the bucket, but such means has proven ineffective and under normal excavating operations, the operator lowers the bucket to the point of digging and frequently, as the bucket is drawn forward and contacts a rocky formation that fails to give, the bucket with its full or partial load, rises upwardly and, when the rock formation breaks away, the bucket falls back to its normal position, striking its bottom against the rocks and bending the bottom inwardly. In a relatively short time, the bottom has been bent inwardly so far, that the bucket fails to perform correctly and it becomes necessary to remove the bucket and by suitable pounding, bend the bottom back to normal position. This action results in a considerable loss of time and is comparatively expensive and under normal rocky excavating, the bucket will require repairing approximately once a week.

An important object of the present invention resides in providing a centrally disposed brace for the bucket that is welded upon the inner surface of the bucket and provides a rigid novel brace to prevent inward bending of the bucket bottom under practically all normal conditions of excavating.

A further object of the invention resides in a cooperating strengthening brace across the outer rear wall of the bucket that prevents bending of the wall inwardly, should the bucket be dropped too suddenly on its end.

A further object of the invention resides in the novel construction of the brace means and the manner of installation whereby the bucket bottom is braced from various angles of impact.

Other important objects and advantages of the invention will be more clearly described and pointed out during the course of the following description, reference being had to the accompanying drawings, wherein is shown the preferred form of the device and wherein like characters of reference are employed to denote like parts throughout.

In the drawings:

Figure 1 is a side elevation of a conventional drag line bucket with the invention applied thereto.

Figure 2 is a top plan view thereof.

Figure 3 is a rear end elevation thereof.

Figure 4 is a transverse sectional view of the bucket, taken on line 4—4 of Figure 1 and looking in the direction of the arrows,

2

Figure 5 is a fragmentary sectional view of the bucket, taken on line 5—5 of Figure 2.

Figure 6 is a fragmentary transverse section, taken on line 6—6 of Figure 5.

Figure 7 is a perspective view illustrating the manner of installing the brace means.

Figure 8 is a perspective view of one side plate of the brace and,

Figure 9 is a perspective view of one of the gussets employed in the brace means.

Referring specifically to the drawings, the numeral 5 designates any standard and conventional drag line excavating bucket, having a bottom 6, side walls 7 and a rear wall 8. The bottom is rounded into the rear wall 8 in arcuate form and the bottom and wall 8 may be formed in a continuous sheet of material, as may also the bottom and side walls. The forward end of the bucket is formed open and the leading edge of the bottom 6 is provided with conventional cutting teeth 9. The forward end is also provided with a conventional yoke 10, having connection with hoisting cables or chains, as is customary. The bucket is also provided with forward clevises 11 for connection with draft cables or chains, while the rear portion of the bucket is supported and controlled by chains 12, connected to swivels 13. The structure so far described is generally conventional with all dragline buckets.

It has been found, that when excavating rock or the like, the bucket when being dragged forwardly for cutting or digging action, will frequently engage a mass that is so hard as to cause the loaded or partially loaded bucket to fulcrum upwardly upon the teeth 9 and, as the rock mass breaks away, the loaded bucket drops back to the horizontal position and strikes the rock surface with considerable force, accelerated by the load in the bucket and causes the bottom of the bucket, adjacent its rear end, to be progressively bent inward. This is understandable, when it is considered that the bucket, plus its load, weighs several thousand pounds. Due to this pounding and bending, it becomes necessary to disconnect and transport the bucket to a point of repair and the bottom then pounded out to its original shape. As the bottom is bent inwardly, the loading and discharge thereof becomes increasingly more difficult and greatly reduces the volume of work possible in the usual working day, which volume is considerably expensive in view of the cost of the machine operator, equipment and the like. The purpose therefore of this invention is to provide a novel brace means within the bucket, that will absorb the external forces of pounding impact to the extent that the bottom and rear wall are adequately braced against inward bending.

The brace of the present invention is rigidly welded in position within the bucket and designated as a whole by the numeral 14. The brace 14 is centrally arranged and extends longitudinally of the bucket, engaging both the bottom wall 6 and rear wall 8 in that area subjected to external forces. The brace consists of a central plate 15, vertically arranged and having a straight upper edge 16 and a lower edge 17 that conforms to the curvature of the bottom as it merges into the rear wall 8. The plate 15 is formed of metal of a suitable gauge calculated to withstand the major external force and the edge 17 is welded throughout its length to the bottom and rear wall of the bucket. Lateral stresses to either side of the plate 15, is absorbed by a plurality of gussets 18, triangular in shape and having their vertical and bottom edges welded to the plate 15 and bottom 6, as shown. The gussets 18 are cut away to provide assembly and welding tongues 19, for a purpose to be described. The gussets 18 are covered by side angularly disposed plates 20, slotted at 21, for the

reception of the tongues 19 at assembly. The plates 20 have a straight upper edge 22 that normally parallels the edge 16 of the plate 15 at assembly and a curved lower edge 23 that conforms to the curvature of the bottom and rear wall 6 and 8 at their point of merging. The plate at assembly is welded along its upper edge 22 throughout its contact with the plate 15 and also throughout its curved edge 23, to the bottom of the bucket. The plate 20 is also welded throughout the engagement of the tongues in the slots 21. As shown, the gussets are positioned in radial form and the number of gussets employed is determined by the size of bucket and the estimated weight thereof and the weight of the estimated load supported within the bucket.

In the assembly of the brace 14, the overall length of the desired brace is determined and the lower edge of the plate 15 is cut to conform to the bottom of the bucket. The plate is then positioned within the bucket in vertical position and welded to the bucket along its entire curved edge 17. The number and sizes of gussets having been determined, they are positioned upon opposite sides of the plate 15 and temporarily supported in angular and radial position in contacting relation with the sides of the plate 15 and the bottom of the bucket. Any suitable template may be employed for the temporary support of the gussets. The gussets are then welded to the plate 15 and the bottom of the bucket throughout the right angular edges. The plates 20, having been preformed, are then positioned over the gussets at both sides of the plate 15, with the tongues 19 seated within the slots 21. In this position, the edge 22 contacts and parallels the edge 16 of the plate 15, while the lower edge 23 contacts the bottom of the bucket throughout its length. The edges 20 and 23 are then welded throughout their length to the edge 16 and bottom of the bucket respectively. The plate 20 is then welded throughout the length of the several tongues of the gussets. It will thus be seen, that a very rigid brace has been provided that is angularly disposed at the rear portion of the bucket in that area found to absorb the major portion of all external forces. The stress of external force is thus transmitted throughout the brace both longitudinally and laterally, while the assembled brace is of inverted V-shape in cross section and offers no obstacle to the loading and unloading of the bucket.

As an additional safeguard against inward bending, should the bucket be dropped forcibly upon its rear wall 8, a transverse horizontally arranged rib 24 is welded to the outer face of the wall 8 at a point above the brace 14. The rib 24 will obviously be notched to engage over the conventional external runners 25 of the bucket, with the engaging edge of the rib being welded throughout its length to the bucket. Gussets 26 are preferably welded to the rib 24 above and below and to the wall 8 of the bucket. An external force striking the rib 24 will be transmitted through the brace 14 longitudinally thereof, with the force being distributed both longitudinally and laterally.

It will be apparent from the foregoing, that a very novel and highly efficient brace means has been provided for drag-line buckets. The brace rigidly supports the bottom and rear wall against inward bending and does not interfere with the loading action of the bucket nor the discharge of such load. The incline of the brace both longitudinally and upon its sides, prevents rocks or the like from catching and hanging in the bucket. It is contemplated that the brace shall be installed within drag-line buckets as original equipment, but the application of the brace to those buckets now in use is simple and cheap to install and greatly adds to the life of the bucket and avoids the very costly delays now encountered in straightening and repairing the buckets after their bottoms have been bent inward.

Since the buckets will not be removed from service periodically for repair, the production will be very considerably increased.

It is to be understood, that the invention is not limited to the precise arrangement shown, but that various changes in the shape, size, materials and methods of assembly may be resorted to as clearly fall within the spirit of the invention or the scope of the subjoined claims.

Having described my invention, what I claim as new and desire to secure by Letters Patent is:

1. Brace means for use with a drag-line excavating bucket of the type that is formed of sheet metal and having a flat bottom wall, vertical side walls and a vertical rear wall, and with the bottom being rounded to merge into the several walls, an internal brace device for rigid positioning within the bucket centrally and longitudinally thereof, the brace device embodying a central plate having an upper straight edge and a curved lower edge that conforms to the merging portion of the bottom, the straight edge being inclined throughout its length from the bottom to the rear wall, outwardly inclined side plates welded to the first named plate along its straight edge and to the bottom, rear wall and rounded area of the bottom, gussets transversely and radially disposed between the plates, the several plates being welded throughout their lower edges to the bucket and the gussets being welded to the plates and to the bucket and an outer rear wall brace that extends transversely and horizontally of the rear wall and is welded thereto throughout its length and gussets above and below the rear wall brace that are welded throughout their contacting engagement with the brace and the rear wall.

2. A bottom and rear wall brace device for use with sheet metal drag-line excavating buckets that have a flat bottom that is rounded to merge into a vertical rear wall, the brace embodying an inverted V-shape in cross section throughout its length, the brace consisting of a flat vertically arranged metallic plate that is positioned centrally and longitudinally of the bucket, the plate having a lower curved edge that conforms to and is welded to the rounded portion of the bottom and the rear wall, the upper edge of the plate being straight and inclined upward throughout its length from the bottom to the rear wall, transversely disposed triangular gussets arranged upon both sides of the plate and welded to the plate and to the bottom, the gussets being disposed radially with the gussets upon opposite sides of the plate being identically arranged, closure plates for positioning over the gussets, interlocking means between the gussets and the closure plates, the closure plates having straight upper edges co-extensive with the upper edge of the first named plate, the closure plates inclined outwardly and downwardly for interlocking engagement with the gussets with their lower edges curved to conform to the rounded bottom portion, the upper straight edges of the closure plates lying in parallel contact with the straight edge of the first named plate, the several plates and gussets being rigidly welded together throughout their contacting engagement and rigidly welded to the bucket throughout their contacting engagement therewith.

3. A bottom and rear wall brace device for use with drag-line excavating buckets of the type that have a flat bottom wall and a rear wall and with the bottom wall being curved to merge into the rear wall, an inverted V-shaped brace adapted to be rigidly positioned in the bucket centrally and longitudinally thereof and connected jointly to the bottom and rear walls, the brace consisting of a flat vertically arranged center plate and downwardly and outwardly inclined side plates, the center plate and the side plates having upper straight edges co-extensive in length and lying in parallel contacting engagement, the lower edges of the several plates being curved to conform to and have contacting engagement throughout their lengths with the bottom, rear wall and curved area, the

upper straight edges jointly being inclined upwardly and rearwardly from the flat bottom to the rear wall, triangular gussets transversely positioned between the plates and upon opposite sides of the center plate, the gussets being disposed in a radial manner, the side plates provided with radial slots corresponding to the radial positioning of the gussets, the gussets having tongues formed thereon that are co-extensive with their co-operating slots, the side plates being positioned in overlying position to cover the gussets with the tongues of the gussets engaging their respective slots, the several plates and gussets and their engaging tongues being welded throughout their area of contacts, the several plates and gussets being welded to the bottom, rear wall and rounded area throughout their points of contact.
